(57) CLAIM

The ornamental design for a bar cart, as shown and described.

DESCRIPTION

FIG. 1 is a front perspective view of a bar cart, showing my new design according to a first embodiment;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is another perspective view thereof;

FIG. 9 is a front perspective view of a bar cart, showing my new design according to a second embodiment;

FIG. 10 is a left side view thereof;

FIG. 11 is a right side view thereof;

FIG. 12 is a front view thereof;

FIG. 13 is a rear view thereof;

FIG. 14 is a top view thereof;

FIG. 15 is a bottom view thereof; and,

FIG. 16 is another perspective view thereof.

The broken lines in the drawings depict portions of the bar cart that form no part of the claimed design.

1 Claim, 16 Drawing Sheets
